UNITED STATES PATENT OFFICE.

JAMES F. McLAUGHLIN, OF PHILADELPHIA, PENNSYLVANIA.

ELECTRIC MOTOR.

SPECIFICATION forming part of Letters Patent No. 375,560, dated December 27, 1887.

Application filed December 16, 1886. Serial No. 221,765. (No model.)

To all whom it may concern:

Be it known that I, JAMES F. McLAUGHLIN, a citizen of the United States, residing in Philadelphia, Pennsylvania, have invented 5 certain Improvements in Electric Motors, of which the following is a specification.

My invention consists of certain improvements in the construction of electric motors, as fully described hereinafter.

10 In the accompanying drawings, Figure 1 is a side view of my improved motor. Fig. 2 is a vertical section on the line 1 2, Fig. 1. Fig. 3 is a vertical section on the line 3 4, Fig. 1; and Fig. 4 is a diagram of the circuits.

15 My improved motor is of that construction in which armatures revolve between fixed field-magnets which are on opposite sides of the armatures.

The frame of the machine consists in the 20 present instance of a base-plate, *a*, and end standards, *a'*, which are provided with bearings for the longitudinal shaft or axis *A*, carrying the armatures and commutators. To these standards *a'* are secured the electro magnets *E E'*, constituting the field-magnets.

Each field-magnet consists of two coils, *e*, having their cores united by the standard *a'*, or by a suitable plate of magnetic metal, so that each field-magnet consists of a horseshoe.

30 The horseshoe field-magnet *E* is arranged in a plane at right angles to the horseshoe field-magnet *E'*, as shown in Fig. 1. I prefer to provide the field-magnets *E E'* with extended pole-pieces *e'*, carried on a radius from the 35 axis of the armature-shaft.

Each armature consists of a pair of electro-magnets, *F F'*, secured to a cruciform metal plate, *f*, mounted on the axis *A*. This plate is of magnetic metal, so that it will form the 40 connecting-plate for the two coils of each magnet to form a horseshoe-magnet corresponding with the horseshoe field-magnets. The two magnets are secured on opposite sides of the same plate *f*, and in planes at right angles to

each other, in order to obtain a better mechanical balance, as well as a more convenient arrangement of parts. The poles of the armatures are provided with extended pole-pieces *f'*, similar to those on the field-magnets.

The armature-shaft carries two commutators, 50 *C*, of any convenient construction. In the present instance each commutator consists of a pair of insulated plates connected to the coils of the corresponding armature. On the periphery of each commutator bear spring 55 commutator-brushes *b*.

The circuits will be clearly understood on reference to Fig. 4, from which it will be seen that the coils of the field-magnets and armatures are in series. Beginning at the binding-post *p*, the circuit is through the coils of the field-magnets *E*, thence to one of the commutator-brushes and armature-coils, and from the second commutator-brush to the coils of the field-magnets *E'* on the other side of the machine. The circuit, as before, is thence through the commutator, armature-coils, and commutator out through the binding-post *p'*.

I claim as my invention—

1. An electric motor having armatures revolving between two field-magnets, the field-magnets being horseshoe-magnets in planes at right angles to each other, and the armatures being also horseshoe-magnets in planes at right angles to each other.

2. The combination of the field-magnets *E* and *E'* with intermediate revolving armatures consisting of electro-magnets carried by a central cruciform plate, the pairs of electro-magnets being on opposite sides of the plate and in planes at right angles to each other.

In testimony whereof I have signed my name to this specification in the presence of two subscribing witnesses.

JAMES F. McLAUGHLIN.
